Specification for Design.

Patented Feb. 21, 1922.

Application filed August 21, 1920. Serial No. 405,211. Term of patent 14 years.

To all whom it may concern:

Be it known that I, AUGUST KLEIN, a citizen of the United States, residing at Camden, in the county of Camden and State of New Jersey, have invented a new, original, and ornamental Design for Finger Rings, of which the following is a specification, reference being had to the accompanying drawings, forming part thereof.

Fig. I, is a top plan view of a finger ring, showing my new design.

Fig. II, is a side view of the same; and Fig. III, an edge view.

I claim:

The ornamental design for a finger ring, as shown.

AUGUST KLEIN.
